(57) **CLAIM**

We claim the ornamental design for a pet food container, as shown and described.

DESCRIPTION

FIG. 1 is a perspective view of a pet food container showing our new design;

FIG. 2 is a top plan view thereof;

FIG. 3 is a front elevational view of FIG. 2; and,

FIG. 4 is a side elevational view thereof.

1 Claim, 2 Drawing Sheets

FIG. 1

FIG. 2

FIG. 3

FIG. 4
